UNITED STATES PATENT OFFICE

124,028

DESIGN FOR A TEXTILE FABRIC

Joseph B. Hoffman, New York, N. Y.

Application September 23, 1940, Serial No. 95,312

Term of patent 3½ years

To all whom it may concern:

Be it known that I, Joseph B. Hoffman, a citizen of the United States, residing in New York city, in the county of New York and State of New York, have invented a new, original, and ornamental Design for a Textile Fabric, of which the following is a specification, reference being had to the accompanying drawings, forming part thereof.

Fig. 1 is a plan view of a textile fabric showing my design and

Fig. 2 is the reverse side thereof.

Fig. 3 is another plan view of Fig. 1 on an enlarged scale.

I claim:

The ornamental design for a textile fabric, substantially as shown.

JOSEPH B. HOFFMAN.
